UNITED STATES PATENT OFFICE.

HENRY HELLMAN AND LEWIS CONDICT BAYLES, OF JOHANNESBURG,
TRANSVAAL.

WATER-SUPPLYING ATTACHMENT FOR ROCK-DRILLING MACHINES.

No. 847,286.

Specification of Letters Patent.

Patented March 12, 1907.

Original application filed July 12, 1905, Serial No. 269,406. Divided and this application filed July 24, 1906. Serial No. 327,471.

To all whom it may concern:

Be it known that we, HENRY HELLMAN and LEWIS CONDICT BAYLES, citizens of the United States, and residents of Johannesburg, Transvaal, have invented certain new and useful Improvements in Water-Supplying Attachments for Rock-Drilling Machines, of which the following is a specification.

This invention relates to rock-drilling machines or engines and to attachments for supplying water through the drill-steel to the cutting extremity thereof with the object of preventing the impregnation of the atmosphere with the dust or minute particles of rock produced when the machine is in operation. The dissemination of this dust, as is well known, deleteriously affects the health of rock-drill operators. Another important feature of the introduction or supplying of water to the cutting-point of the drill is that it increases the efficiency of the machine by washing away the detritus, so that the bit contacts directly with the solid rock and is not impeded by the cuttings. It also ¹⁵ serves the cutting end of the drill and so obviates the necessity for as frequent renewal of the drills or bits as when water is not used.

The object of the invention is to provide means for the accomplishment of the purposes ²⁰ specified which shall be simple and efficient in operation and to obviate the defects of the devices at present in use.

The attachment which is positioned on the shank or rear end of the drill-steel is readily ²⁵ detachable therefrom in the operation of renewing the drills, and such arrangement has the further advantage that it obviates the necessity for the passing of the water through any part of the machine or engine proper, so ³⁰ that drills or bits may be used in the same machine without the water-supplying attachment—as, for example, in the drilling of downwardly-inclined holes when such water-supply may not be requisite or desired.

The invention constituting the subject-matter of the present application is a division ³⁵ of an application filed by us on the 12th of July, 1905, bearing official Serial No. 269,406.

With the object of facilitating the detailed description of the invention we append a sheet of explanatory drawings, wherein—

Figure 1 represents a rock-drilling ma-

chine or engine, partly in section, with the invention applied thereto; and Fig. 2 is a detached view of the water-swivel shown open. ⁵⁵

In the drawing, 1 designates a hollow cylindrical protecting-casing, and 2 the power-cylinder, which is slidably and rotatably mounted in said casing. ⁶⁰

Round the protecting-casing 1 is clamped the sleeve or band 3, which is shown constructed with the cone 4 for mounting the apparatus on an ordinary column or in any other suitable support. The sleeve 3 is split ⁶⁵ and formed with the lugs 5, between which is placed a bolt 6, which serves for drawing the two lugs 5 together to tighten the sleeve 3 round the casing 1.

The casing 1 is constructed with an inlet-port 7 at or in proximity to the rear end, which serves for connecting an ordinary throttle-valve through which the compressed air or other actuating fluid is admitted to the rear end of the casing 1. The casing 1 is also ⁷⁰ constructed at its forward end with holes 8, which serve as exhaust-ports for the fluid exhausting into the casing 1 from the power-cylinder 2. Holes 9 are also formed at or ⁷⁵ about the center of the casing 1, which form escape-ports for the actuating fluid under certain circumstances. The casing 1 is shown constructed of slightly smaller diameter at the forward end to make a sliding fit with the exterior of the power-cylinder. ⁸⁰ 2

Instead of the construction shown it will be evident that a bush, cap, or end piece may be fitted on or in the end of the casing to form a bearing for the forward end of the power-cylinder 2. ⁸⁵

38 is a port which serves alternately as a supply and exhaust port for the forward end of the power-cylinder 2, and 39 an exhaust-port in the power-cylinder 2, communicating with the interior of the casing 1. ⁹⁰

50 is an extension of the power-cylinder 2, to which the latter is rotatably connected, and 54 a cap or nut on the rear end of the casing 1. ⁹⁵

69 is the handle for retracting the extension 50, and with it the power-cylinder 2 in its protecting-casing 1, and 74 73 are screw and nut, respectively, for securing the handle 69 to the extension 50. ¹⁰⁰

The power-cylinder 2 is counterbored or ¹⁰⁵ made of somewhat larger diameter at the for-

ward end, wherein is located the impact-piece 10, which receives and transmits the impacts of the power-piston or percussive reciprocating member 11 to the shank of the 5 drill or bit. The counterbore 12 forms, with the bore 13, in which the power-piston 11 reciprocates, an abutment or shoulder which limits the rearward movement of the impact-piece 10. The counterbore 12 at the forward 10 end is made taper, and into it is fitted a taper-bush 14, which is made with a square or polygonal parallel bore 15. The drill-steel 16 is at its forward extremity constructed or fashioned into any ordinary and suitable 15 form of drill or bit, as a "chisel-bit" or "star-bit," and at its rear end or shank is made of square or polygonal section to correspond to the bore 15 of the bush 14, in which it is loosely positioned. This construction insures 20 a synchronous rotation of the bit 16 with the power-cylinder 2, while allowing the bit 16 to move longitudinally of the power-cylinder 2 within certain limits. The inner end of the shank 17 abuts the forward end of 25 the impact-piece 10 in the working of the machine, so that the repeated impacts of the percussive reciprocating member 11 are immediately transmitted from the impact-piece 10 to the shank of the drill-steel 16.

30 In the drill-steel 16 in advance of the part 17 of square or polygonal section is formed an annular recess 20, said recess forming annular shoulders or projections 18 round the drill-steel. The drill-steel 16 is provided with 35 a longitudinal hole or port 19 and with two (more or less) transverse ports 21, communicating at their inner ends with said longitudinal port 19 and at their outer ends with the recess 20.

40 It will be obvious that instead of making the ports 21 at right angles to the longitudinal port 19 they may be angularly disposed in relation thereto and in a forward direction.

Arranged round the drill-steel 16 and positioned in the annular recess 20 and between the shoulders or abutments 18 is a detachable swivel or swivel-piece 22. The swivel is constructed of the two parts 23 24, hinged together at 25. The two parts are connected to secure 50 the swivel 22 in the recess 20 by means of a ferrule 26, which is carried by the one part 24 and slides up over the end of the other part. This provides a very ready means for clamping the swivel 22 round the drill-steel 16. The swivel 22 is recessed on the inside to 55 form an annular space 29 between it and the reduced portion of the drill-steel. With this space 29 the port (or ports) 21 in the recess 20 in the steel communicates. The part 24 of the swivel is constructed with an extension 30, which forms a stem to which the hose or other flexible pipe 31 is fixed by means of the hose-clamp or other suitable device 32. Through the extension 30 is formed a hole 33, 60 leading into the annular space 29. The other

end of the hose-pipe 31 is placed in communication with any convenient source of water-supply, preferably under pressure.

When the machine is in operation and it is desired to use the water-supply to the bore-hole, then the water, preferably under pressure, is admitted through the medium of the hose or other flexible pipe 31 to the annular recess 20 in the water-swivel, whence it passes by the water ducts or transverse ports 75 21 along the longitudinal hole or port 19 to the cutting end of the drill and issuing from said latter port is directed against the rock at the bottom of the hole, and so washes the detritus away from the cutting-face of the tool. 80

What we claim as our invention, and desire to protect by Letters Patent, is—

1. In a device such as described, in combination, a drill-steel having a longitudinal hole therein and an annular recess and a transverse port communicating at its outer end with said recess and at its inner end with said longitudinal hole, a swivel-piece mounted in said recess, said swivel-piece consisting of two parts hinged together, means for detachably connecting said parts around the steel, and means for conducting water under pressure to said swivel-piece. 90

2. In a device such as described, in combination, a drill-steel having a longitudinal hole therein and an annular recess and a transverse port communicating at its outer end with said recess and at its inner end with said longitudinal hole, a swivel-piece mounted in said recess, said swivel-piece consisting of two parts hinged together, said swivel having an internal recess around the drill-steel which internal recess communicates with the transverse hole in the steel, the two parts of said swivel-piece being detachably connected in the recess in the steel, and means for introducing liquid under pressure to the cavity in the swivel-piece. 105

3. In a device such as described, in combination, a drill-steel having a longitudinal port therein and an annular recess and a transverse port communicating at its outer end with said recess and at its inner end communicating with said longitudinal hole, a swivel-piece comprising two parts hinged together, said swivel having an internal recess round the drill-steel in communication with the transverse port, means for detachably connecting the swivel in the recess in the drill-steel, and means for conducting liquid under pressure to the recess in the swivel-piece. 110

4. In a device such as described, in combination, a drill-steel having a longitudinal hole therein and an annular recess and a plurality of transverse ports communicating at their outer ends with said recess and at their inner ends with said longitudinal hole, a swivel-piece in two parts hinged together, said swivel-piece having an annular internal recess round the drill-steel and communicat- 125 130

ing with the transverse ports, means for detachably connecting the swivel-piece in the recess in the drill-steel, the swivel-piece having a hose-stem and a hose-pipe attached to said stem communicating with a source of liquid-supply under pressure, as set forth.

5. In a device such as described, in combination, a drill-steel having a longitudinal hole leading to the cutting end thereof and an annular recess forming round the drill-steel annular shoulders or projections and a plurality of transverse ports communicating at their outer ends with said recess and at their inner ends with said longitudinal hole, a swivel-piece mounted in the recess between the shoulders or abutments, said swivel-piece having an internal cavity in communication with the transverse holes in the drill-steel and comprising two parts hinged together, means for detachably connecting the swivel in the recess in the drill-steel, said means comprising a ferrule or nut, the swivel-piece having a hose-stem, a hose-pipe, a clamp fixing said pipe to the stem, the pipe communicating with a source of liquid-supply under pressure, as set forth.

6. In a device such as described, in combination, a power-cylinder having at its forward end an aperture of polygonal transverse section, a drill-steel having a longitudinal hole leading to the cutting end and its rear extremity of polygonal transverse section corresponding to the aperture in the front end of the cylinder in which it fits so that it is compelled to rotate therewith, a swivel-piece rotatable mounted on the rear end of said drill-steel and in communication with said longitudinal hole, and means for conducting liquid under pressure to said swivel-piece.

7. In a device such as described, in combination, a power-cylinder having at its forward end an aperture of polygonal transverse section, a drill-steel having longitudinal and transverse holes, and its rear extremity of polygonal transverse section corresponding to the aperture in the front end of the power-cylinder in which it fits so that it is compelled to rotate therewith, a swivel-piece on said steel in communication with

the longitudinal and transverse holes in the latter, and means for conducting water under pressure to said swivel.

8. In a device such as described, in combination, a power-cylinder, a reciprocating percussive member therein, an impact-piece located in the forward end of the cylinder and adapted to receive and transmit the impacts of the percussive member to the drill-steel, the power-cylinder having an aperture 55 of polygonal transverse section in front of said impact-piece, a drill-steel of polygonal transverse section at its rear extremity projected into the correspondingly-shaped aperture in the front end of the power-cylinder, 60 said drill-steel having a longitudinal hole and transverse holes and an annular recess with which said transverse holes communicate, a swivel-piece located in said annular recess and means for conducting water under pressure 65 to said swivel-piece.

9. In a device such as described, in combination, a power-cylinder, a reciprocating percussive member therein, an impact-piece located in the forward end of the power-cylinder 70 and adapted to receive and transmit the impacts of the percussive member to the drill-steel, a bush fitted in the forward end of the power-cylinder in front of the impact-piece said bush being made with a hole of 75 polygonal transverse section, a drill-steel of polygonal transverse section at its rear extremity projected into the correspondingly-shaped bush in the front end of the power-cylinder, said drill-steel having a longitudinal 80 hole and transverse holes and an annular recess with which said transverse holes communicate, a swivel-piece located in said annular recess having an internal cavity in 85 communication with the transverse holes, 90 and means for conducting water under pressure to said swivel-piece.

In witness whereof we have hereunto set our hands in the presence of two subscribing witnesses.
